AUTOMATIC ELEVATOR PLANT.

1,085,937.

Specification of Letters Patent.

Patented Feb. 3, 1914.

Application filed September 21, 1908. Serial No. 453,999.

To all whom it may concern:

Be it known that we, CHARLES O. PEARSON and AUGUST SUNDH, citizens of the United States, and residents, respectively, 5 of the borough of Brooklyn, in the county of Kings, city and State of New York, United States of America, and of the city of Yonkers, in the county of Westchester, State of New York, United States of America, have 10 invented certain new and useful Improvements in Automatic Elevator Plants, of which the following is a specification.

Our invention relates to an automatic elevator plant, and its object is to provide 15 a complete elevator installation including a power plant, and a control system, for both the elevator and its power plant by means of which various mechanisms may be controlled by the simple manipulation of an 20 electric switch or push-button.

More specifically, the object of this invention is to provide a system of control in which an internal combustion engine may be started at will and be automatically controlled, and the power developed by such 25 engine be utilized in actuating an elevator.

Further objects of our invention will appear in the following specification in which we will describe the construction and arrangement of certain apparatus shown in 30 the accompanying drawings as an illustration of a method in which the invention may be carried into effect, and the novel features of which we will set forth in the appended claims.

Referring to the drawings, Figure 1 is a side elevation of an elevator apparatus and a power plant, together with some associated mechanisms, and with certain controlling 35 switches with their connecting circuits shown diagrammatically. In Fig. 2 we have shown in side elevation, partly in section, an elevator installation made according to our invention, in which is shown the manner in 40 which the parts thereof may be situated in separate buildings. Fig. 3 is a sectional side elevation of a portion of automatic floor stop switch which is a part of our improved control system. The connection between the 45 spark timer mechanism of the engine and one of the magnets of the electrical control

system is shown in side elevation in Fig. 4, and a part of this connection is shown in plan view in Fig. 5. Fig. 6 is a side elevation, partly in section, of an engine starting device, a speed governor, and other parts which are connected with the engine. A detail of the engine starting mechanism is shown in section in Fig. 7. Fig. 8 is a sectional end elevation of the starting device. 60 Fig. 9 is a side elevation of a pressure pump and pressure regulator with some of the parts shown in section to more clearly show their construction.

Like characters of reference designate corresponding parts in all of the figures. 65

10 designates the foundation or base upon which the various parts of the power plant are mounted.

11 is an internal combustion engine, and 70 12 is its shaft. This engine is shown as a four-cycle four-cylinder gasoline engine, but any other suitable form or type of engine may be substituted if desired.

13 is its intake or supply pipe. 75

14 is a carburetor to which gasoline is led by a pipe 15 from a supply tank 16 which, if desired, may be buried underground as shown in Figs. 1 and 2.

17 is the engine exhaust pipe which leads 80 the burnt gases off through a muffler 18.

19 designates the spark-plugs for the engine.

20 is the ordinary spark timer mechanism which is driven from the engine shaft 85 through a vertical shaft 21 and suitable gearing. This mechanism is connected by a rod 22 and a bell-crank lever 23 with an electromagnetically actuated device which will be described hereinafter.

24 is an induction coil. Its secondary leads 25 and 26 connect, respectively, through the spark timing mechanism 20, with the spark-plugs 19 and with the frame 90 of the engine to which the lead 26 is grounded.

27 is a storage battery, and 28 and 29 are its leads which are connected with the primary of the induction coil and with other parts of the apparatus by circuits which we 100 will point out later.

Between the carburetor 14 and the intake

of the engine is a regulating valve 30. This is shown somewhat in detail in Fig. 6 in which it appears that 31 is a piston valve cut away at 32 and interposed in the passage 5 supply pipe 13. 33 is a piston rod extending upward from the piston to a lever 34 which is pivoted at 35. 36 is a centrifugal governor which is arranged to move the lever 34 and, through the connections just pointed 10 out, to actuate the governor valve 30 and another valve which will be pointed out later. This governor is driven by a vertical shaft 37 by means of a bevel gear 38 on the lower end of shaft 37, which gear is 15 in mesh with a similar bevel gear 39 on the end of engine shaft 12.

41 designates the cylinder of a pressure pump 40. Within this cylinder is a piston 42 which is driven by an eccentric 43 upon 20 engine shaft 12.

44 is an intake valve in the pump of cylinder 41, and 45 is the outlet valve. The outlet or passage is connected by a pipe 46 with the pressure tank 47.

25 48 is a diaphragm pressure regulator which is arranged to actuate a relief valve 49 whenever the pressure within tank 47 exceeds the desired amount.

50 is a fluid pressure starting device for 30 the engine. It comprises a cylinder 51 within which is the piston 52 pressed upward by means of a compression spring 53. The lower end of the piston rod is constructed to form a toothed rack 54 which is in mesh 35 with a gear 55 loosely mounted upon the engine shaft 12. The gear 55 is provided with a flange 56 on one side, upon which is pivotally supported a pawl 57. This pawl is spring-pressed into engagement with a 40 ratchet-wheel 58 whenever the flange is rotated. The wheel 58 is keyed or otherwise rigidly affixed to the engine shaft 12.

59 is a pin arranged to strike on the pawl 57 to raise the pawl out of engagement with 45 the ratchet-wheel while the starting device is at rest.

When air or other fluid pressure is admitted to the top of cylinder 51, the piston will be depressed and, through the connections 50 above described, will cause the engine shaft to be rotated. The engine will then draw in an explosive mixture and will start to run under its own power. As soon as pressure is released from cylinder 51, the spring 55 53 will return the parts of the starting device to their initial positions.

60 60 designates a circulating pump for the engine which is driven by the latter and is arranged to draw water from a tank 61 60 through a pipe 62 and to force it through pipe 63 to the cooling jacket of the engine cylinders.

64 is the return pipe from the water jacket to the tank 61.

70 designates an elevator hoisting apparatus which comprises an electric motor 71 and a hoisting drum 72 connected together by suitable gearing.

73 is the drum shaft.

A car 74 and counterweight 75 are connected with the hoisting drum by cables in the usual manner.

76 is a pinion gear on the end of shaft 73 which is in mesh with a slidable toothed bar 77. On one part of this bar a pair of 75 contact plates 78 and 79 are mounted. These plates are insulated from the bar and from each other.

65 designates a brake-pulley which is rigidly mounted upon the motor shaft.

66 is a brake-shoe mounted upon a pivoted lever 67 which is pressed upward by a spring 68 so that the brake-shoe is in contact with the pulley 65.

69 is an electromagnet or solenoid, so arranged that when it is energized it will pull the brake lever down against the action of spring 68 and release the brake.

80 designates the door to the elevator shaft at the lower landing or floor. 80^A is a similar door at the middle floor; 80^B is the door at the upper landing.

81, 81^A and 81^B are door contacts through which one of the circuits of the control system passes when the doors are all closed. 95 When any of the doors are open, its door contact is opened, as shown at 81^A, at the second floor.

82 is a push-button in the hall at the first floor, which is normally held open by a 100 spring, but which may be manually pressed against a stationary contact 83. 84 is a similar push-button at the second floor, and 85 the contact against which it may be moved. 86 and 87 are, respectively, the 105 push-button and its contact at the third floor. 88 is a conductor connecting these three push-buttons. More landings with their push-buttons might be shown, but we believe that three of these are sufficient to 110 illustrate the operation of the invention.

90 is a conductor leading to three push-buttons 91, 92 and 93 in the car, which push-buttons correspond with the three landings at which the car is arranged to stop. The 115 conductor 90 is connected with these three push-buttons through a safety push-button 94 which is arranged to break the circuit to them when it is depressed.

95 is a contact for the button 91 which is 120 connected by a conductor 96 with the stationary contact 83.

97 is the contact for button 92 and this is connected by a conductor 98 with the stationary contact 85.

99 is the contact for button 93 and is connected by conductor 99 with the stationary contact 87.

100 is the winding of a floor-control switch magnet, one end of which is connected with the conductor 96 and its other end connected with a common return wire 101. This floor-
 5 control magnet is shown on a larger scale and somewhat in detail in Fig. 3, in which figure it may be seen that it comprises a core 102 which is normally held in a raised position by a spring 103. It also has a contact
 10 rod 104 depending from its core and arranged to be moved down into position to touch one of the sliding contacts 78 or 79 when the winding 100 is energized, and when either of these contacts is directly below it.
 15 The conductor 96 is also connected with the contact rod 104. 105 is the winding of a similar floor-control magnet which is connected with the conductors 98 and 101, and controls a contact rod 106 which is also connected with conductor 98. 107 is the winding of a third floor-control magnet which is connected with the conductors 89 and 101. This magnet controls contact rod 108 which is connected with conductor 89.
 20
 25 Returning to the power plant, it may be seen that an electric generator 110 is directly connected with the engine 11 by having its shaft coupled to the engine shaft 12. 111 and 112 are the leads from its armature, and 113 and 114 the leads from its shunt field winding.
 30

120 and 121 are the windings of an electromagnetically actuated reversing switch. These are arranged to raise certain insulated
 35 contact plates against stationary contacts in a manner which will be pointed out in describing the operation of our invention.

130 and 131 are the windings of an electromagnet which is arranged when energized, to cause the motor 11 to be started and to perform other functions in conjunction therewith. 140 is the winding of a controlling magnet which is arranged to actuate the spark timing mechanism and the spark coil
 40 for the engine, and to coöperate with the other parts of the control system. These magnets control certain circuits and apparatus which we will point out more fully in describing the operation of the invention, which we will now proceed to do.
 45

50 If a person on the first floor of a building in which the elevator is installed pushes button 82 against contact 83, a circuit will thereby be completed, if all the hatchway doors are closed, from battery 27, through conductors 28, 150 and 88, the push-button and its contact, conductor 96, through winding 100 and conductors 101 and 29, back to the battery. This will energize the first floor control magnet and cause it to pull conductor 104 down against the sliding contact 79 which will be in the position shown if the car 74 is opposite the second floor. This will now complete a circuit from the battery

through the conductors already pointed out, to and through conductor 150. Thence, the new circuit will continue through conductor 151, winding 130 of the starting switch, and conductor 152 to the slideable contact plate 79. Thence, it will continue through the magnet winding 100 and conductor 101 back to the battery. The operator may then release button 82 without breaking the circuit through magnet 100. As the magnet winding 130 is now energized, it will raise the core or plunger 132. This will open valve 133 which is interposed between the pressure supply pipe 115 leading from the pressure tank 47, and pressure pipe 116 which leads to the top of cylinder 51 of the starting device. This, as has been pointed out, will rotate the engine. At the same time contact plate 134 will be moved up until it bridges stationary contacts 135 and 136 and thereby closes a circuit by conductors 153 and 154 through the primary winding of the induction coil 24. This, then, will supply current for the igniter mechanism of the engine, so that the latter will run under its own power. At the same time, another contact plate 137 will be raised up until it bridges stationary contacts 138 and 139. This, through conductors 155 and 156, will connect the winding 140 across the battery. Energizing magnet 140 causes it to raise its core 141 and, through the latter and bell-crank lever 23 and the connections heretofore pointed out, to actuate the spark timer mechanism to advance the spark and to thereby increase the speed of the engine in the usual manner. The contact plate 142 will be raised up against stationary contacts 143 and 144 to close the generator armature leads 111 and 112 across the battery 27 by means of conductors 28 and 117. The contact plate 145 will also be raised up against contacts 146 and 147 to complete the circuit through winding 121 of the reversing switch. This circuit runs from the battery through conductors 28, 150 and 151, contact 147, contact plate 145, and contact 146, conductor 148, winding 121, conductors 149 and 152, sliding contact plate 79, contact rod 104, winding 100, and conductors 101 and 29 back to the battery. The operations above described will cause the engine to be automatically started and brought up to its normal speed which will be governed by the throttle valve 30. At the same time the governor will actuate a valve 158 through a connection 159 to cut off the pressure supply from cylinder 51 and to open same to the air so that the spring 53 may return the piston 52 and the parts which it controls to their normal positions. The generator 110 will now be driven by the engine to supply electrical energy for driving the elevator motor 71 and for energizing the battery 27 and the con-
 55

trol circuits. This will be because its shunt field winding, which is connected across the armature leads, will also be connected across the battery 27 by the circuits shown as soon as contact plate 142 bridges stationary contacts 143 and 144. The elevator motor 71 is arranged to be driven by the current generated by the dynamo 110. To attain this end the motor armature leads 160 and 161, which are indicated in the drawings by heavy broken lines, and the motor field leads 162 and 163, which are indicated in the drawings by light broken lines, are led to the reversing switch and connected thereto in the manner shown. The circuit through winding 121, which has been traced, will cause the right-hand side of the reversing switch to be actuated. This will cause the dynamo main 112 to be connected with the motor armature lead 161 by contact plate 122, and the main 111 through conductor 29 and contact plate 123 with the motor armature lead 160. The motor field lead 163 is permanently connected with conductor 29 which is connected with one of the mains of the generator, and when the contact plate 124 is raised, the motor field lead 162 will be connected thereby with the other main 112 from the generator. Therefore, the elevator motor will be supplied with current, and as the brake magnet 69, which is connected by conductors 118 and 119 with the conductors 160 and 161, will also be energized to release the brake, the motor will then rotate in one direction. The connections between the elevator motor and car 74 are such that this rotation of the motor will cause the car to be moved downward. The downward movement of the car will cause the sliding bar 77 to be moved to the left, and the parts are so proportioned that when the car has about reached the lower landing, the slidable contact 79 will be moved out of contact with the contact rod 104, thus breaking the circuits which it controls. This means that the magnet windings 100, 130, 140 and 121 will be deenergized, and that the parts which they control will return to their first positions. The current from the motor will thus be cut off and the brake applied, so that the elevator-car will automatically come to rest at the first floor. The current supplying the ignition sparks for the engine will also be cut off so that the engine will also come to rest. In the meantime any excess of electrical energy which has been developed by the generator 110 will be stored in battery 27, and the pump 40 will have recharged the pressure tank 47. The electrical energy stored in the battery 27 will also be available in starting the elevator, as at this part of the operation an excess of current is often desired. It may be seen that if any of the hatchway doors 65 had been opened, the operating circuit would

have been broken, so that the car could not have been started.

A similar operation to that above described would take place if a passenger should enter the car at the second floor, and, after having closed the door 80^A, should push the button 91. In that case the current for first energizing winding 100, will pass from conductor 150, through conductor 90 and the push-button 91 and its contact 95 to conductor 96; otherwise the operation will be the same as before more specifically described. If the button 86 on the top floor had been closed against its contact 87, a similar operation would have taken place, except that in this case the winding 107 would have been energized to pull contact rod 108 down against slidable contact 78 which, through conductor 157, would close the circuit through winding 131 of the starting switch. This would have the same effect as the energization of winding 130 had upon the starting switch, but is connected to energize the winding 120 instead of the winding 121 of the reversing switch. Two cores are shown for the starting switch, but this is done only for the sake of clearness in tracing the two circuits through windings 130 and 131. As the left-hand side of the reversing switch will now be energized it will raise contact plates 125, 126 and 127 and these will close the same circuits as those previously described. But in this case the motor armature leads 160 and 161 will be connected, respectively, with conductors 112 and 29 so that the current will pass through the motor armature in the opposite direction to that before traced, and will cause the motor to rotate in the opposite direction or in the direction to raise the car. When the car reaches the top floor it will be stopped by the slidable contact plate 78 having been moved over to the right and from under the contact rod 108. The contact rod 106 will touch either contact 78 or 79, according to the position of the car, so that if the car is above the second floor when push-button 84 is depressed, it will come down to that floor, or, if the car is below the second floor it will come up. Of course, any desired number of landings may be equipped with the controlling buttons and their corresponding floor controlling magnets, but we believe that the three stations which are illustrated and described are sufficient to fully disclose this part of our invention.

We have shown an elevator apparatus and a power plant therefor which may be installed together, or may be two separate installations removed from each other, or in different buildings, if desired. The latter arrangement is shown in Fig. 2. This, in many instances, is desirable. In such cases a switch-board 164 may be placed near the elevator hoisting apparatus which may en-

tirely disconnect the power plant if desired or render the elevator machine inoperative.

When elevators are desired in country residences, where no supply of energy for driving such apparatus is available, this invention is especially useful. The power plant may be set up at a point removed from the dwelling and connected therewith only by electrical conductors. All the advantages of an automatic electric push-button elevator may thus be obtained in places hitherto without such conveniences.

Other types of elevators than that herein described may be installed under this invention as its scope is not at all limited by the specific illustration shown. The economy of operation is apparent, for the power plant is running only during such times as it is needed for driving the elevator.

This invention increases the scope of application of gasoline or other internal combustion engines and opens a new field of usefulness for them. No skilled attendant is necessary for such an installation as we have described as the entire operation of the power plant is automatic and the elevator is started by the simple manipulation of a push-button and stops automatically at the desired floor, at the same time causing the control system to shut down the power plant until such a time as it is desired to use the elevator again.

What we claim is:

1. An elevator comprising a hoisting motor, a prime mover for supplying energy to said motor, manually controlled devices for starting and controlling the prime mover to start and control the action of the elevator, and means for stopping the elevator and the prime mover together.

2. An elevator comprising a hoisting motor, a prime mover for supplying energy to said motor, manually controlled devices at the elevator for starting and controlling the prime mover to start and control the action of the elevator, and automatic means for stopping the elevator and the prime mover together.

3. An elevator comprising a hoisting motor, a separate prime mover therefor, connections between the prime mover and the elevator motor for supplying energy to said motor, a single control system for both the prime mover and the elevator motor, said system comprising manually controlled devices at the elevator, connections between said devices and the prime mover arranged to start the prime mover and the elevator motor, and devices for stopping the prime mover and the elevator together.

4. An elevator comprising a hoisting motor, a separate prime mover therefor, connections between the prime mover and the elevator motor for supplying energy to said motor, a single control system for both the

prime mover and the elevator motor, said system comprising manually controlled devices at the elevator, and connections between said devices and the prime mover arranged to start the prime mover and the elevator motor; means for controlling the prime mover and the direction of movement of the elevator, and automatically actuated devices for stopping the prime mover and the elevator together.

5. An elevator comprising an electric motor, an electric generator for supplying current to the motor, electric connections between the elevator and the generator, a single electrical control system for both the elevator and the generator, said system comprising manually controlled switches, and electromagnetically actuated switches whereby the generator and the elevator may be started together.

6. An elevator comprising an electric motor, an electric generator for supplying current to the motor, electric connections between the elevator and the generator, a single electrical control system for both the elevator and the generator, said system comprising manually controlled switches and electromagnetically actuated switches whereby the generator and the elevator may be started together at will, and circuit-breakers arranged to be automatically actuated by the elevator for stopping the elevator and the generator together.

7. An elevator comprising a motor and a car arranged to stop at different floors, an engine driven generator for supplying energy to the elevator motor, a control system for both the elevator and the generator, said system comprising manually controlled devices arranged to start the generator and the elevator together, and automatically actuated devices arranged to stop the elevator and the generator together when the car reaches a desired floor.

8. An elevator comprising a motor and a car arranged to stop at different floors, a generator for supplying energy to the elevator motor, a control system for both the elevator and the generator, said system comprising manually controlled devices at the elevator arranged to start the generator and the elevator together, and devices automatically actuated by the movement of the car arranged to stop the elevator and the generator together when the car reaches a desired floor.

9. An elevator comprising an electric motor and a car arranged to stop at different floors, a generator for supplying electric energy to the elevator motor, an electrical control system for both the elevator and the generator, said system comprising circuits, manually controlled switches in said circuits at the elevator, and means controlled by said switches for starting the generator

and the elevator together; and floor controlled switches automatically actuated by the movement of the car arranged to stop the elevator and the generator together 5 when the car reaches a desired floor.

10. An elevator, a motor therefor, a power plant for supplying energy to the motor, said power plant comprising an internal combustion engine, intermediate connections between the power plant and the motor; a control system for the power plant and the motor, said system comprising devices for starting the power plant to start the motor, and other devices for stopping 15 the power plant and the motor together.

11. An elevator, a motor therefor and a car arranged to stop at different floors, a power plant for supplying the energy to the motor, said power plant comprising an internal combustion engine, intermediate connections between the power plant and the motor; a control system for the power plant and the motor, said control system comprising manual devices for starting the 20 power plant to start the motor, and automatic devices for stopping the power plant and the motor together when the car reaches a desired floor.

12. In an elevator a car and an electric motor; an internal combustion engine connected to a dynamo for supplying current to said motor, a starting device for the engine, electrical connections between the dynamo and the motor, and a control system 30 comprising devices for simultaneously starting, stopping and controlling the engine and motor, connections being so arranged that the elevator motor is started, stopped and controlled by the similar actions of the 35 engine.

13. In an elevator a car and an electric motor; an internal combustion engine and a dynamo driven thereby, a device for starting the engine, and a control system connecting the motor and the dynamo, said system comprising manually controlled switches arranged to control the engine starting device and the motor, and devices automatically actuated by the movement of the motor for 45 stopping the engine.

14. An elevator, a motor for operating the elevator, a source of electric power comprising an engine and connected dynamo, a starting device for the engine arranged to be 50 actuated by energy generated by the engine itself, a control system for the elevator and the source of electric power, said control system being energized by a supply of current generated by the engine, and comprising 55 manually operated devices for controlling the engine starting device and the elevator, and automatically actuated devices for stopping the engine and the elevator together.

65 15. An elevator, a power plant therefor,

said power plant comprising an engine, a starting device for the engine, an electrical control system for the elevator and the power plant, means also driven by the engine for generating an electrical supply for 70 said system, said system comprising manually operated devices for controlling the engine starting device and the elevator, and automatically actuated devices for stopping the engine and the elevator together. 75

16. An elevator, a power plant therefor, said power plant comprising an engine, a starting device for the engine, a dynamo driven by the engine, a storage battery, and a control system for the elevator and the 80 power plant, said control system being energized by the electrical energy from the battery and comprising electromagnetic devices for controlling the engine starting device and the elevator. 85

17. An elevator having a car arranged to stop at different floors, and an electric motor; a power plant for the elevator, said power plant comprising an internal combustion engine, a starting device for the engine, 90 an electropneumatic valve arranged to control the starting device, a dynamo driven by the engine, a storage battery connected therewith, and a control system for the elevator and the power plant, said control system being energized by electrical energy from the storage battery and comprising manually operated switches, circuits connecting said switches with the electropneumatic valve, whereby the power plant and the elevator may be started, and other switches automatically actuated by the movement of the car for stopping the power plant and the elevator when the car reaches a desired floor. 95 100

18. In an elevator having a car arranged to stop at different floors, an electric motor arranged to drive the elevator; an internal combustion engine connected to a dynamo, a starting device for the engine, an electropneumatic valve for controlling the starting device, a storage battery connected with the dynamo, a throttle valve for controlling the speed of the engine, a centrifugal governor driven by the engine and arranged to actuate the throttle valve; and a control system for the elevator motor, engine and dynamo, said control system being energized by electrical energy from the storage battery and comprising manually operated 110 switches, circuit connecting said switches with the electropneumatic valve whereby the engine and the elevator motor may be started, and other switches automatically actuated by the movement of the car for stopping the engine and the elevator motor when the car reaches a desired floor. 115 120

19. In an elevator a car arranged to stop at different floors, and an electric motor; an internal combustion engine, a starting de- 125 130

- vice for the engine, an electropneumatic valve for controlling the starting device, a dynamo driven by the engine, a storage battery connected with the dynamo, a throttle valve for controlling the speed of the engine, a centrifugal governor driven by the engine and arranged to actuate the throttle valve; a control system for the elevator and the engine, said control system being energized by electrical energy from the storage battery and comprising means for actuating the starting device to start the engine and to thereby start the elevator motor, and a valve actuated by the centrifugal governor arranged to release the starting device after the engine has attained a desired speed, said control system also comprising automatic switches for stopping the elevator and the engine when the car reaches a desired floor.
20. In an electric elevator, an electric motor, a hoisting apparatus and a car; a generator for the elevator, an automatic control system for the elevator, said control system comprising push-buttons arranged to start the generator and the elevator, and floor-control switches arranged to stop the generator and the elevator.
21. In an electric elevator, an electric motor, a generator for the motor, electric connections between the motor and the generator, and an automatic control system for the motor, said control system comprising push-buttons arranged to start the generator and the motor, and floor-control switches arranged to stop the generator and the motor.
22. In an electric hoisting elevator, an electric motor, a car arranged to stop at different floors; a generator for the elevator motor, a wiring system for the elevator motor and the generator, a push-button at each floor, each of said push-buttons being connected with devices arranged to start the generator and the elevator motor, and means actuated by the movement of the hoisting apparatus to stop the elevator motor and the generator when the car reaches the floor at which a push-button has been depressed.
23. In an electric elevator, an electric motor, a hoisting apparatus, and a car arranged to stop at different floors; a generator for the motor and the generator, a push-button at each floor, a floor magnet corresponding with each floor, each of said push-buttons being arranged, when depressed, to energize one of said floor magnets, and means for thereby starting the generator and the elevator; and switches automatically actuated by the movement of the hoisting apparatus arranged to deenergize said floor magnet when the car has reached the floor at which the button has been depressed.
24. In an electric elevator, an electric motor, a hoisting apparatus, and a car arranged to stop at different floors; a generator adapted to supply current for the elevator, a wiring system for the elevator and the generator, a push-button at each floor, a floor-magnet corresponding with each floor, circuits therefor, a pair of slideable contact-plates arranged to coöperate with the floor-magnets each of said push-buttons being arranged, when depressed, to energize one of the floor magnets and to close a circuit through one of the slideable contact-plates, and means for thereby starting the generator to start the elevator in one direction; means for causing said slideable contact-plates to be moved by the movement of the hoisting apparatus to break said floor-magnet circuit when the car has reached the floor at which a push-button has been depressed and to cause the elevator and the generator to stop.
25. In an electric elevator, an electric motor, a hoisting apparatus, and a car arranged to stop at different floors; a hatchway door at each floor, door contacts actuated by said doors; a generator adapted to supply current for the elevator, a wiring system for the elevator and the generator, a push-button at each floor, a plurality of push-buttons in the car corresponding with each floor, a floor-magnet corresponding with each floor, circuits therefor, a pair of slideable contact-plates arranged to coöperate with said floor magnets, means for causing each of said push-buttons when depressed to energize one of the floor magnets to close a circuit from the door-contacts and through one of the slideable contacts to thereby start the generator and to start the elevator in one direction; means for causing said slideable contacts to be moved by the movement of the hoisting apparatus to break said floor magnet circuit when the car has reached the floor for which a button has been depressed, and to cause the elevator and the generator to stop.
26. An elevator, a power plant therefor comprising an engine, electroresponsive devices arranged to control the starting of the engine, the speed thereof, and the direction of travel of the elevator, and a control system for controlling said electroresponsive devices.
27. An elevator having an electric hoisting motor, a generator for supplying current to said motor, a control system for both the elevator and the generator, said control system comprising an electromagnetically actuated starting switch, a speed control switch for the generator, and a reversing switch for the elevator.
28. An elevator, a power plant therefor comprising an internal combustion engine, a starting device therefor, a sparking mechanism for the engine, and a control system for both the elevator and the power plant,

said system comprising an electromagnetically actuated switch arranged to control the starting device current for the sparking mechanism to start and to stop the engine; 5 and a reversing switch for the elevator.

29. In an elevator, an electric motor, a power plant for the elevator comprising an internal combustion engine, a starting device therefor, a sparking mechanism for the 10 engine, and a control system for the elevator and the power plant, said system comprising an electromagnetically actuated switch arranged to control the starting device and the current for the sparking mechanism to start 15 and to stop the engine; an electromagnetically actuated switch for shifting the sparking mechanism, and an electromagnetically actuated reversing switch for the elevator motor.

20 30. In an electric elevator, an electric motor, a hoisting apparatus, and a car; a power plant for the elevator, said power plant comprising an internal combustion engine and a dynamo driven thereby, a device 25 for starting the engine, a wiring system connecting the motor and the dynamo; and an automatic push-button control system arranged to control said starting means, said system comprising means for controlling the 30 engine-starting device, and a reversing switch for the elevator motor.

31. In an electric elevator, an electric motor, a hoisting apparatus, and a car arranged to stop at different floors; a power plant for 35 the elevator, said power plant comprising an engine, a starting device for the engine arranged to be actuated by energy generated by the engine itself, a control system for the elevator and the power plant, said control 40 system also being energized by a supply generated by the engine and comprising a push-button at each floor, and means for causing each of said push-buttons, when depressed, to start the power plant and the elevator, and other means actuated by the movement of the hoisting apparatus to stop the elevator and the power plant when the car reaches the floor at which a push-button has been depressed.

50 32. In an electric elevator, an electric motor, a hoisting apparatus, and a car arranged to stop at different floors; a power plant for the elevator, said power plant comprising an engine, a starting device for the engine, 55 a dynamo driven by the engine, a control system for the elevator and the power plant, said control system being energized by the electrical energy from the dynamo and comprising a push-button at each floor, a floor- 60 magnet corresponding with each floor, circuits therefor, and means for causing each of said push-buttons, when depressed, to energize one of said floor magnets; means controlled by the energization of said magnet

for actuating said engine-starting device to 65 start the power plant and the elevator, and means actuated by the movement of the hoisting apparatus for automatically deenergizing said floor magnet when the car reaches the floor for which a push-button 70 has been depressed.

33. In an electric elevator, an electric motor, a hoisting apparatus, and a car arranged to stop at different floors; a power plant for the elevator, said power plant comprising 75 an internal combustion engine, a starting device for the engine, a dynamo driven by the engine, a storage battery connected therewith, an electropneumatic valve for controlling the engine-starting device, and a 80 control system for the engine and the power plant, said control system being energized by electrical energy from the storage battery, and comprising a push-button at each floor; a floor-magnet corresponding with 85 each floor, circuits therefor, a pair of slideable contact-plates arranged to coöperate with said floor-magnets, and means for causing each of said push-buttons, when depressed, to energize one of the floor magnets 90 to close a circuit through one of the slideable contact-plates, and to actuate the electropneumatic valve to thereby start the power plant and to start the elevator in one direction; means for moving said slideable contact-plates by the movement of the hoisting apparatus to automatically break said circuit when the car has reached a floor at which a push-button has been depressed to cause the elevator and the power plant to 100 stop.

34. In an electric elevator, an electric motor, a hoisting apparatus, and a car arranged to stop at different floors; a hatchway door at each floor, door contacts actuated by said door; a power plant for the elevator, said power plant comprising an internal combustion engine, a starting device for the engine, an electropneumatic valve for controlling the starting device, a dynamo driven 105 by the engine, means for automatically governing the speed of the engine, and a control system for the elevator and the power plant, said control system being energized by the dynamo and comprising a push-button at each floor, a plurality of push-buttons in the car corresponding with each floor, a floor-magnet corresponding with each floor, a pair of slideable contact-plates arranged to coöperate with said floor-magnets, means for causing each of said push-buttons, when depressed, to energize one of the floor-magnets to close a circuit through the door contacts and through one of the slideable contact-plates, and means for 110 thereby actuating the electropneumatic valve to start the engine and to start the elevator in one direction; and means for mov- 115 120 125

ing said slidable contact-plate by the movement of the hoisting apparatus to break said circuit when the car has reached a floor for which a push-button has been depressed to 5 cause the elevator and the power plant to stop.

In testimony whereof we have signed our

names to this specification in the presence of two subscribing witnesses.

CHARLES O. PEARSON.
AUGUST SUNDH.
